C. G. HAWLEY & E. K. BAKER.

MUFFLER,

APPLICATION FILED DEO. 21. 1908.

972,190.

Patented Oct. 11, 1910.

UNITED STATES PATENT OFFICE.

CHARLES GILBERT HAWLEY AND ERLE K. BAKER, OF CHICAGO, ILLINOIS.

MUFFLER.

972,190.

Specification of Letters Patent.

Patented Oct. 11, 1910.

Application filed December 21, 1908. Serial No. 468,507.

To all whom it may concern:

Be it known that we, CHARLES G. HAWLEY and ERLE K. BAKER, citizens of the United States, and residents of Chicago, Cook county, Illinois, have invented certain new and useful Improvements in Mufflers, of which the following is a full, clear, and exact description, such as will enable others skilled in the art to make and use the same.

10 Our invention relates to improvements in mufflers for engines, particularly gas engines and has special reference to mufflers for use on automobiles.

The object of our invention is to provide means for attachment to the exhaust pipe of an explosion engine or the like and adapted to effectually muffle or silence the noise of the explosions and the escaping exhaust gases.

20 A further object of our invention is to provide simple and effective means for relieving the pressure of gas in the muffler pipe adjacent to the muffler.

Still another object of the invention is to provide means for diverting exhaust gases from the muffler, at will, for use in operating a signal such as a whistle or horn.

Specific object of our invention is to provide a combined muffler, muffler cut-out and signal means, which shall be of low cost, of neat appearance and compact form and which shall be both efficient and durable.

Our invention consists generally in a muffler and muffler parts of the construction and combination of parts hereinafter fully described and particularly pointed out in the appended claims.

The invention will be more readily understood by reference to the accompanying drawings forming a part of this specification, and in which—

Figure 1 illustrates a complete muffler embodying our invention; Fig. 2 is an end view thereof; Fig. 3 is a longitudinal section on the line X—X of Fig. 2; Fig. 4 is a transverse section on the line Y—Y of Fig. 3; Fig. 5 is an enlarged detail showing the manner in which the valves are loosely attached to their operating members; and Fig. 6 is a longitudinal section on the line Z—Z of Fig. 3 viewed in the direction of the arrows.

The invention in the preferred form illustrated in the drawings may be briefly described as comprising a body portion, drum or shell together with heads at opposite ends

thereof, one of said heads preferably carrying both a muffler cut-out and safety valve and a signal valve. As will be better understood from what follows, the several features of our invention may be embodied in different forms than those herein shown, and furthermore certain of the parts and features are adapted for use with coacting members of forms not herein shown. For these reasons we do not confine or limit our invention to the specific construction or the complete assemblage of parts herein shown and described.

Referring now to the drawings, 2 represents a shell or body of the muffler, 3 the forward end or head thereof, 4 the rear end or head and 5, 5 are rods or bolts which bind the heads upon the shell, 3^a is a gas inlet box or chamber integral with the head 3 and preferably centrally disposed thereon in alignment with the axis of the shell 2. The main portion of the box 3^a is preferably rectangular in cross section as shown in Figs. 2 and 4; its forward end 3^b is preferably reduced to 70 circular form and contains a circular opening 3^c to receive the rear end of the exhaust or muffler pipe from the engine. The box 3^a has an outlet port, passage or opening 3^d in one of its sides and the flange or boss 75 which projects from the side of the box has its end machine finished to form a valve seat 3^e. 6 is the muffler cut-out and safety valve, being preferably a round flat disk which seats on the seat 3^e. A valve arm or 80 bell crank 6^f is pivoted on the side of the box 3^a and its arm 6^g is connected to the disk or plate 6 by means of a loose rivet or stud 6^h. The rivet is preferably rigidly fastened in the disk and is loosely attached to 85 the operating arm or part (see Fig. 5). The valve is normally held shut by a strong spring 7 attached to the other arm of the bell crank or lever and extending back to a clip 7ⁱ on the shell 2. The valve operating 90 means preferably comprises a pull cord 6^a attached to the outer or free end of the bell crank. It will be noted that one side of the box is preferably slightly off set to give room for the member 8, it being desirable that said member 8, when in normal position, shall be entirely removed from the direct path of the gases entering at the opening 3^c. The member 8 is rigidly attached to the rocking shaft or stem 8^j which extends through the box 100 and has its outer end 8^k formed into an operating crank. A strong spring 9 attached

to the arm 8" and to the shell 2 by a clip 9', serves to normally hold the rocking shaft or crank and the member 8 in the position shown by full lines in the several figures of the drawing. A pull cord, or the like, 10 attached to the free end of the crank or operating lever 8" is used for turning the crank and hence the member 8 to the position shown by dotted lines (see Fig. 3). 10 When the member 8 is in this position it forms an obstruction or closure across and within the box 3^a and diverts the gases into the signal passage about to be described. Said passage is constituted by a threaded 15 nipple 11 which is screwed into a hole provided therefor in the side of the box. The end of the nipple projects inward beyond the inner wall of the box and is machine finished to form a valve seat 11' adjacent to the outer side of the member or deflecting wing 8. The wing or gas intercepting member may seat directly upon the end of the nipple, but we preferably employ a disk valve 8''' like unto the valve 6 and attached to the wing 25 8 by a similar loose rivet or stud 8''', of the construction shown in Fig. 5. Obviously the spring 9, which acts on the shaft 8' and member 8, normally holds the self seating disk 8''' firmly against its seat on the end of 30 the nipple 11. The threaded outer end of the nipple 11 serves as a convenient means of attaching a horn, whistle or other gas operated signal to the muffler and an adequate supply of gas for the signal is available 35 when the member 8 is moved away from the valve seat and across the main gas passage to temporarily put the muffler chamber out of service by diverting the gases into the port or passage 11. We prefer that the muffler cut-out port 3^a shall be back of the member 8 rather than opposite the end of said member and as the member 8 is adapted to contact the opposite side of the box and is of substantially the same width as the box (see 40 45 Figs. 4 and 6), practically the entire stream of gas will be diverted to the signal when the signal valve is opened. It will be understood that the seat for the valve 8 may be formed on the inner wall of the box 3^a as that portion may be readily reached with a tool inserted through the port 3^a, but for reasons of compactness and light weight we prefer to use the seat-forming nipple 11. The head 4 on the rear end of the shell may 50 contain a series of perforations, according to present practice in some quarters, but we prefer to provide it with a central boss 4' to receive the outlet or terminal pipe or tube 4''. Circular ribs 12 may be provided on 55 the inner surface of the heads 3 and 4 to receive internal cylinders, when such are desired.

From the foregoing, it will be clear that we have in our invention obtained the several 60 objects set forth in the opening of the speci-

fication; our invention in its complete preferred form being the only device that need be attached to a muffler or exhaust pipe to accomplish the stated purposes efficiently and at low cost.

70

Having thus described our invention we claim as new and desire to secure by Letters Patent:

1. In a muffler head the combination with a central passage, of side ports for said head, valve means for closing one of said ports and means common to said central passage and said other port for closing one and opening the other.

75

2. In a muffler the combination with an exhaust chamber and a head therefor having three gas discharge outlets, one of said outlets leading to said exhaust chamber, another of said outlets leading to the atmosphere and another of said outlets being 85 adapted for connection to a signaling device, valve means for closing said second mentioned outlet and separate valve means common to said first and last mentioned outlets for closing one and opening the other.

80

3. In a valve for gas engine exhaust pipes, the combination with an inlet box having a central passage for exhaust gases and two outlets, of valve means for controlling the passage of gases through one of said outlets and separate valve means common to said central passage and said other outlet for opening one and closing the other.

95

4. In a muffler the combination with an exhaust chamber, of a head of said chamber, 100 an inlet box for said head adapted to discharge gases directly into said exhaust chamber, a signaling device associated with said head, valve means for intercepting the gases in said inlet box and for diverting them into said signaling device, a discharge opening for said inlet box adapted to discharge gases directly into the atmosphere, and valve means for closing said opening.

105

5. The combination with a muffler of a head for said muffler, a chamber in said head leading directly to said muffler, a side port for said head adapted to discharge gases from said chamber into the atmosphere, another port for said chamber and a signaling device associated therewith, and means associated with said port for diverting gases from said chamber into said signaling device.

115

6. In a muffler for gas engines the combination with an exhaust chamber, of a head for such chamber comprising an inlet box and ports leading from said box, one of said ports being adapted to discharge gases directly into the atmosphere and the other of said ports being adapted to discharge gases into a signaling device, a signaling device associated with said last mentioned port and means in said inlet box for obstructing the passage of gases into said muffler and for di-

120

125

130

verting them into the port leading to said signaling device.

7. The improvements herein described, comprising a muffler front end head having an inlet box for attachment to a muffler pipe and provided with outlet ports or passages in its sides, valve seats being formed at the inner and outer ends of said ports respectively, in combination with an intercepting valve stem at the inner end of said box adjacent to the side thereof containing the port having the seat at its inner end, means for rocking said stem, a wing or intercepting valve attached to said stem and adapted to swing across and obstruct the passage in said box, said valve adapted to close on said inner seat, a valve adapted to close upon the seat at the outer end of the other port, a spring normally closing the same and means for operating the last mentioned valve, substantially as described.

8. The improvements herein described, comprising a signal valve for attachment to a muffler pipe containing a passage which is a continuation thereof and provided with a port in its side, a valve seat being formed at the inner end of said port, in combination with a valve stem at the exit end of said passage adjacent to the wall containing said port, an intercepting valve or wing on said stem normally parallel with said seat, but adapted to be projected across said passage, a stud projecting from said wing and a flat disk loosely attached to the wing by said stud and adapted to close upon said seat, substantially as described.

9. The improvements herein described,

comprising a muffler front end head, in combination with an inwardly opening signal valve and an outwardly opening muffler cut-out thereon, a rear head, a shell or drum, and means binding said heads upon said drum, substantially as described.

10. The improvements herein described, comprising a muffler front end head, in combination with an inwardly opening signal valve and an outwardly opening muffler cut-out thereon, a rear head, a shell or drum, means binding said heads upon said drum, valve operating levers on said front head and springs respectively connecting them with the sides of said shell, substantially as described.

11. In a muffler the combination with an exhaust chamber, of a head for said chamber, a chamber in said head adapted to normally discharge gases into said exhaust chamber, a signaling device, a port in said head leading to said signaling device, valve means in said head chamber for intercepting the passage of gases to said exhaust chamber and for directing said gases into said signaling device, a second port in said head opening directly into the atmosphere and separate means for closing said port.

In testimony whereof, we have hereunto set our hands this 19th day of December, 1908, in the presence of the subscribing witnesses.

CHARLES GILBERT HAWLEY.
ERLE K. BAKER.
